BOARD GAME AND PLAYING PIECES AFFORDING LIMITED INITIAL MOVES OF PLAYING PIECES

Howard W. Fisher, 11760 S. Wallace,
Chicago, Ill. 60628
Filed Apr. 12, 1965, Ser. No. 447,145
4 Claims. (Cl. 273—131)

ABSTRACT OF THE DISCLOSURE

A board game apparatus having a board divided into generally trapezoidal sections or playing areas each of different color and each subdivided into playing spaces identified by railroad designating indicia on which are placed playing pieces identified by matching indicia. At the outset only four central vacant spaces are provided so as to limit the initial moves of playing pieces. The object is to jump playing pieces of opponent so as to remove them from the game, thus furnishing more and more vacant spaces facilitating moves. A single play consists of moves which may be made horizontally, or vertically, or diagonally, or a combination of any two or more of such moves may be made simultaneously if vacant spaces permit. When a playing piece reaches its corresponding space, it is removed from the board and replaced by a station marker.

My invention relates to board game apparatus and is intended to provide a stimulant to calculate advance planning and thinking, or in other words mental gymnastics and exercises.

An important object of my invention is to provide a game for a group of players for purposes of amusement or pastime, as well as for developing methods and strategy to be employed in playing said game.

Another object of my invention is to provide a game of the aforementioned character employing a board having a playing field subdivided into a number of playing sections or areas, each of said playing sections or areas being further subdivided into a number of playing spaces.

Another object of my invention is to provide in a board apparatus a limited number of vacant spaces at its geometric center so that at the outset the playing of the game is greatly restricted but other and more distant moves of playing pieces become available as the game progresses.

A further object of my invention is to provide in a board apparatus a number of rectangular playing areas which permit the movement of playing pieces horizontally, vertically, or diagonally or a combination of any two or all three directions, continually dependent upon the vacancies created upon said board, thus opening paths of travel.

It is a further object of my invention to provide game apparatus which can be manufactured economically in quantity production.

Other and ancillary objects of my invention may be had by reference to the following description read in the light of the accompanying drawings in which:

FIG. 1 is a plan view of a preferred form of my invention;

FIG. 2 is a plan view of one of the playing pieces employed in playing the game;

FIG. 3 is a bottom view of FIG. 2;

FIG. 4 is a plan view of another of the playing pieces used in the game;

FIG. 5 is a bottom view of FIG. 4;

FIG. 6 is a view showing a move after roads have been cleared; and

FIG. 7 is an enlarged fragmentary view of a portion of the board member comprising my invention.

2

Referring to the various views, my invention consists of a board member (FIG. 1) designated 6, the playing sections or areas as shown at 7, 8, 9 and 10 indicating respectively the colors of the playing pieces 21 and 25 to be employed, i.e., red, orange, green and yellow. The player electing to play with the red playing pieces will move toward and find his objective in the red area, whereas the player selecting the orange playing pieces will move toward the orange area.

The red area and the other colored component areas are substantially of geometric configuration known as trapezoidal shape, the red area being confined between divisional lines 13 and 14, the orange area being encompassed by division lines 13 and 16, the green area being isolated by lines 16 and 15, and the yellow area being confined by lines 15 and 14.

It should be noted that I have designated the playing rectangles in each playing area as follows: A designates all playing rectangles in the green area, B designates the playing rectangles or spaces in the red area, C designates the playing spaces in the orange area, and D represents all playing spaces in the yellow area.

Each playing area has fifteen playing spaces, and each playing space is marked as shown in FIGURE 7 with indicia representing the name of a railroad; for example, the red playing area confined between 13 and 14 has markings designating the following railroads: Frisco, Santa Fe, Union Pacific, Burlington, Great Northern, Milwaukee Road, Northern Pacific, Southern Pacific, Western Pacific, Great Western, Rio Grande, Missabe, Kansas City Southern, Sooner and Fury; the playing pieces 21 colored red have markings identical with the above and are placed on the green playing section confined between lines 15 and 16. B on the drawing represents all the foregoing railroads.

The green playing area confined between lines 15 and 16 has each of its playing spaces marked with the insignia of a railroad, as for example Monon, L & N, Erie, M & N, Rutland, Akron Canton Youngstown, Lehigh Valley R.R., Nickel Plate Road, Main Central, Lehigh New England, N. Y. Central, Long Island R.R., Pennsylvania R.R., B. & O., and Atlantic Coast Lin; the playing pieces 21 colored green are marked identically with the foregoing insignia and are placed on the red playing area confined between lines 13 and 14. A on the drawing represents all the foregoing railroads.

Consequently it can be seen that each player is provided with playing pieces which should be directed to travel toward a station or destination on the opposite side of the board.

The player who selected the orange sector lying between lines 16 and 13 plays toward that sector. The orange playing area has markings designating the following railroads: Peoria Gateway, C & E I, Minneapolis & St. Louis, C and O, Wabash, Soo Line, Rock Island, Duluth South Shore, Spokane Portland & Seattle, Canadian Pacific, North Western, L. S. & I., Canadian National Railways, Lackawanna Railroad, The D & H; the playing pieces 21 colored orange have markings identical with the foregoing and are placed on the yellow playing area. C on the drawing represents all of the aforementioned railroads.

The player selecting the yellow sector or area plays toward the yellow section defined by lines 14 and 15; said yellow area is provided with markings designating the following railroads: Florida East Coast Railway, Seaboard Railroad, Georgia Railroad, Georgia Central, Cotton Belt Route, THB Ry. Co., Texas Mexican Ry., Texas and Pacific, Savannah & Atlanta, K I T, The Southern, The Katy R.R., Missouri Pacific Lines, Illinois Central, Alton & Southern; the playing pieces 21 colored yellow

possess identical markings as hereinbefore enumerated and are placed on the orange playing area confined by lines 13 and 16. D on the drawing represents the names of all the aforementioned railroads.

Each player selects his fifteen playing pieces 21 and places them in spaces 12 in the sector opposite that representing the color chosen by or assigned to him.

At the center of the board member 6 are vacant areas 17, 18, 19 and 20. The board member 6 encompasses sixty-four playing spaces 12. Sixty of these playing spaces 12 are occupied by playing pieces 21 of the players, namely, fifteen playing pieces 21 for each player. The players then determine the rotation of play, each player making a single move.

Playing pieces 21 at the outset can move only into central spaces 17, 18, 19 or 20, one space at a time. Thus it can be seen that initially the game is highly restrictive and very slow progress can be made. The playing pieces may jump those of an opposing player by moving either horizontally, vertically or diagonally. The board provides, therefore, horizontal railroads, vertical railroads and diagonal railroads.

As the game progresses, and jumps are resorted to by the players, the playing pieces that have been jumped over are removed, thus weakening opponent's chances of winning. Hence it becomes apparent that more and more of the board makes available playing spaces 12 and opens up horizontal, vertical and diagonal railroads. When this occurs a player must study the field, for if he can jump one of his opponents, he may continue to travel on open roads through devious horizontal, vertical or diagonal roads, as will be hereinafter elucidated with reference to FIG. 6. When a player, subsequent to one or more plays, moves a marker 21 to its destination, he removes the marker 21 and replaces it with a station marker 25, which creates a block since it may not be jumped. When play reaches a stalemate or impasse, and no further moves can be made, the winner is then determined by the number of station markers he has on the board. The station markers 25 are colored red, green, yellow and orange and are available to each player as needed.

The playing pieces generally designated 21 comprise configuratively the forward appearance of a locomotive, being made of wood or plastic by molding or jig sawing a smoke stack portion 23, a coiter or steam generator portion 22, and a cow catcher portion 24, the piece being identified by indicia representing a railroad.

The station markers 25 are made of wood or plastic and are substantially quadrilateral as shown at 26 and have the design 27 imprinted thereupon and identifying a railroad station.

It can readily be seen that a board member with the names of the various railroads and playing pieces 21 of varied colors identified with similar indicia, as well as the colored station markers, present an attractive as well as an interesting appearance.

The board member 6 may be bisected at 11 so that it may be folded, thus occupying less space in transit or shipment.

The game has been described as it would be played by four players; however, two players may also play the game in which event each player uses one half of the board divided at the fold line 11 and one selects playing pieces 21 to place on the area constituted by the bottom half of FIG. 1 on the drawing, namely, below fold line 11, said playing pieces 21 being positioned on lower section D, section A and lower section C and having corresponding destination points or stations marked on the upper section above fold line 11, i.e., upper section D, section B and upper section C. The player using the other playing pieces 21 positions them also on his section without precalculation and without reference to the destination points on the opposite side. It is this one feature of the game which compels each game to be played differently. This game, unlike chess or checkers, can not be

completed in any predetermined manner. If two players engage in the playing of the game, each player has 30 playing pieces 21, allowing the spaces 17, 18, 19 and 20 to remain vacant to permit initial moves. Sector lines 13, 14, 15 and 16 are ignored.

After many moves have been made and the board 6, see FIG. 6, has four of opponent's playing pieces 21 in the spaces indicated at 29, 30, 31 and 32, if it is a player's turn to play the piece indicated at 33 he may follow the path of solid line arrows 35 and in one move reach his destination at space 28 and place station marker 25 thereon; in making the move he follows path 35 and successively jumps as well as eliminates playing pieces 30, 29, 31 and 32, thus reaching his destination at 28. This merely illustrates how many turns and jumps may be made in one move over the roads horizontally, vertically and diagonally. It should be noted, for example, that if station marker 25 were not in place on the board, the path followed by said player could have taken the direction of dotted line arrows 34.

The railroad names mentioned are merely exemplary any any other railroad designations may be substituted therefor.

Although I have herein described the structure and rules preferably to be employed in playing the game, the rules may be modified to make the game more difficult or to make it simpler.

It should be noted that when the game is started, each player has available only five moves to the central vacant areas, namely, two straight line moves and three diagonal moves. This permits other moves to be made into the areas or spaces 12 vacated by the initial moves. Then after some jumps are made and playing pieces are removed greater freedom for making moves is made available to either or both players. As destinations are reached by either or both of the players and station markers are placed on the board, which occupy spaces 12 until the game is completed, said station markers limit the moves of players and require calculation of devious paths to be followed to reach a particular destination. The foregoing features lend interest to the game since a player may utilize defensive play strategy in blocking paths freed through play and preventing his adversary from playing offensively in trying to reach particular destinations.

Even though the invention has been described in its preferred form with a certain degree of particularity, it is understood that the present disclosure has been made only by way of example and that changes, modifications and alterations could be resorted to without departing from the spirit and scope of the invention defined in the subjoined claims.

Having thus described and revealed my invention, what I claim and desire to secure by Letters Patent is:

1. A board game apparatus of the character described comprising a board member subdivided into a plurality of playing areas each identified by a different color, each of said playing areas being subdivided into a like number of playing spaces, said board having only four unmarked spaces at the geometric center thereof to limit initial moves of playing pieces on said board member, and a number of playing pieces for placement on said playing spaces, each marked space bearing a different indicium and each playing piece bearing a different indicium matching one of those applied to said playing spaces, and a number of distinguishable groups of markers of different formation than said playing pieces whereby a playing piece may be replaced by a marker.

2. A board game apparatus of the character described comprising a board member subdivided into a plurality of playing areas each identified by a different color, each of said playing areas being of substantially trapezoidal configuration and being subdivided into a like number of playing spaces, said board having only four unmarked spaces at the geometric center thereof to limit initial moves of playing pieces on said board member, and a

number of playing pieces for placement on said playing spaces, each marked space bearing a different indicium and each playing piece bearing a different indicium matching one of those applied to said playing spaces, and a number of distinguishable groups of markers of different formation than said playing pieces whereby a playing piece may be replaced by a marker.

3. A board game apparatus of the character described comprising a board member subdivided into a plurality of playing areas, each identified by a different color, said playing areas being of generally trapezoidal configuration positioned contiguously and being subdivided into a like number of playing spaces, leaving only four unmarked spaces at the geometric center of the board to limit initial moves of playing pieces on said board member, and a number of playing pieces for placement on said playing spaces, each marked space bearing a different indicium and each playing piece bearing a different indicium matching one of those applied to said playing spaces, and a number of distinguishable groups of markers of different formation than said playing pieces whereby a playing piece may be replaced by a marker.

4. A board game apparatus of the character described, comprising a board member subdivided into a number of playing areas, each of said playing areas being subdivided into a like number of playing spaces, each identified by different railroad indicia, said board having only unmarked spaces to limit initial moves of playing pieces on said board member, a number of playing pieces equal to

5 the number of playing spaces and each identified by different railroad indicia each matching one of the indicia on said playing spaces, and a number of distinguishable groups of station markers of different formation than said playing pieces.
